UNITED STATES PATENT OFFICE.

MAX WENZEL, OF SPREMBERG, GERMANY.

APPARATUS FOR SEPARATING THE FOREMOST THREAD IN THE LEASE OF TEXTILE WARPS.

1,207,249.

Specification of Letters Patent.

Patented Dec. 5, 1916.

Application filed January 27, 1915. Serial No. 4,760.

To all whom it may concern:

Be it known that I, MAX WENZEL, a citizen of the Empire of Germany, residing at No. 13 Forstenerstrasse, Spremberg, near Lausitz, Kingdom of Prussia, Empire of Germany, have invented new and useful Improvements in Apparatus for Separating the Foremost Thread in the Lease of Textile Warps, of which the following is a specification.

My invention relates to a process for separating and feeding forward the foremost thread in leases of textile warps.

According to my invention the movement 15 of the thread along the lease bars is employed in order to separate the foremost thread from the remaining threads. Hitherto the separation of the thread has exclusively been effected by all the oppositely disposed threads being pushed or forced back 20 along the lease bars. According to my invention, however, the movement of the thread to be separated is effected forwardly with the threads lying in the lease similarly 25 to the thread to be separated, while the other lease threads are held back.

With the method hitherto employed of moving all the threads, with the exception 30 of that to be separated, to the rear, it is not possible with fibrous thread materials, especially with loosely twisted wool-threads, and also with loose threads and the like which easily bind and cohere to obtain by the simple movement of the threads along the lease 35 bars, a sufficient gap for the insertion of the tools and for grasping and feeding forward the separated foremost thread, because the thread to be separated coheres to the others and is drawn backward with same. Other 40 means are therefore necessary in order to with certainty completely separate the foremost thread in the lease and to maintain its distance from the remaining threads sufficiently great to allow of the insertion of the 45 working tools for the feeding forward of the separated thread. The whole mechanism is thus rendered more complicated and the speed of working is reduced. With the new process, however, it is attained that by 50 means of the crossing of the retained threads which do not lie similarly with the thread to be separated, with those threads which do lie similarly with the thread to be separated, those threads which lie similarly with 55 the thread to be separated are prevented

from following the latter which is thus positively released from the remaining threads, and between the separated thread and the remaining similarly lying threads there is formed in the center of the lease a completely free intermediate space sufficing for inserting the means for the forward feeding of the separated thread. 60

The process according to the present invention for separating the foremost thread 65 in the thread-lease permits of a hitherto unattainable working speed and consequently requires means for the further feeding of the separated thread, which are capable of working with certainty at a considerably 70 higher speed than means hitherto known. According to the present invention the separated thread is blown away from the lease by means of compressed air toward suction nozzles which hold the thread in a 75 position in which it is with certainty grasped by a gripper-hook which executes the usual gripper-hook movement, *i. e.*, a swinging motion in the vertical plane and a longitudinal movement in the direction of 80 the lease rods. The compressed air nozzles and the suction nozzles are arranged in mouth-shaped parts of a swinging arm whose mouth is open toward the lease. In 85 said mouth are situated the compressed air nozzles opposite to the suction nozzle arranged in the throat of the mouth, and the pipings to both kinds of nozzles are controlled by the swinging movement of the 90 swinging arm through which they pass. 90

When the gripper has grasped the thread held by the air currents, the swinging arm swings with the nozzles out of the path through which the thread is further guided, and the gripper transfers the grasped thread 95 to a stepwise moved gripper-chain which guides the thread to the manipulating device and after its manipulation to a pair of gripper-hooks of which the one leads the thread to the other hook which is to hold 100 the now prepared thread.

A simple device for carrying into effect the separating process according to the present invention consists of comb-like tools which in addition to a movement along the 105 lease bars have also movements vertical to the plane of the chain and operate in such a manner that always one of said tools, engaging in the initial position in the threads lying dissimilarly with the thread to be 110

separated, holds back these latter, while the other tool which engages the thread to be separated and the threads lying similarly with same, is moved forward and submits the thread at the end of its forward movement to the influence of the air currents which hold back the separated thread, while the remaining threads, in consequence of their tension, fly back. The comb is thereupon returned to its initial position in which it again comes into engagement with the appertaining warp threads, while the other comb executes its forward movement in the same manner.

15 In the accompanying drawings Figure 1 is a front view, Fig. 2 is a side view, and Fig. 3 is a side view partly in section along the line A—B of Fig. 1 of the whole device for separating and further feeding the foremost thread in the thread-lease, Fig. 4 is a front view of the swinging arm with the mouth provided with pressure and suction nozzles, Figs. 5 and 6 are side views in different positions of the swinging arm according to Fig. 4, and Fig. 7 is a section on the line C—D of Fig. 5 in the direction of the arrow, Fig. 8 is a detail of the comb-motion in elevation, Figs. 9—15 are elevational dia-grammatical views which illustrate the different steps in the process, while Figs. 16—18 show the further feeding of the separated thread in side view, in different positions of the appertaining tools.

30 In all the figures similar parts are indicated by similar references.

K, K' are the two lease rods, and *a* is the one lease thread, and *b* the other lease thread. The threads of each group lie similarly with respect to each other. Parallel to the lease rods there are arranged above same and in the same frame walls 2 and 3 which are interconnected by means of cross-members 4 and 5, the slides 6 and 7 in recessed guides 8 and 9 and movable along the lease bars. They are connected by means of links 10 and 11 with the longer arms 12 and 14 of bell crank levers 12, 13 and 14, 15 which are pivotally arranged upon a shaft 16 mounted in the frame walls. Their shorter arms 13 and 15 are provided with adjusting slots 17, 17' in which are adjustably arranged bolts 18, 18' with which engage eccentrics 19 and 20. The latter are displaced 180° with relation to each other and secured on a common shaft 21 which, in the manner to be described hereinafter, is rotated for half a revolution on each working operation, so that the two slides 6 and 7 execute opposite movements along the lease bars. On the side of each slide 6 and 7 is provided a pivot 23 with which engages the appertaining links 10 and 11. Upon these pivots is further swingably arranged a double-armed lever 24, 25. The arm 24 of this lever carries a lateral pin 26 upon which acts

a spring 27 tending to force this arm downward. At the free end of the arm 24 is provided a comb *c* and *d* preferably adjustable in the vertical direction. This comb possesses two or more prongs, for example four prongs, of which the foremost prong *c* or *d* (see also Figs. 9—15) is longer than the remaining prongs which themselves are of equal length. The block carrying the prongs of the comb is provided with an adjusting slot 28 through which passes an adjusting screw 29 secured to the arm 24, and provided with nut 30. The block is prevented from turning by bearing at one side on a lateral projection 31 of the arm 24. The latter possesses further at the head end a projection 32 with a slot 33 through which passes a locking pawl 34 which is swingably mounted upon a pivot 35 on the corresponding slide 6 or 7 and which said pawl is under the influence of a spring 36 tending to force same into the locking position. The locking nose 37 of the pawl 34 comes into its locking position under the front cross-bar of the projection 32 of the arm 24 in order to thus hold the arm 24 at a determined height, while the slide 6 or 7 is drawn backward. The release of the pawl 34 is effected on the completion of the return movement by an adjustable stop 38, for example a stud in the cross-bar 4 of the frame, the position of said stud being assured by a lock-nut 39. When released from the pawl 34, the arm 24 is forced with the comb *c* or *d* into its deepest position.

For raising the arm 24 with the appertaining comb into the highest position there is provided for each lever an arm 40. The two arms are mounted upon a common shaft 41 mounted in the frame walls and in Fig. 3 cover each other. To the shaft 41 is imparted a swinging movement from a cam 42 on the driving shaft 22 against the circumference of which is pressed a roller 43 on the roller 44 by means of a spring 45. Said spring is secured at one end with a pin 46 in the frame wall 3 and at the other end to a pin 47 on the connecting rod 44 whose one end is forked for the purpose of being guided on the shaft 22, while the other end is jointedly connected to an arm 48 on the shaft 41. The arms 40 act upon the arms 25 of the two-armed lever 24, 25 by the intermediary of adjusting screws 49 situated in eyes 40¹ at the end of the arm 40, by means of which adjusting screws the arm 40 is adjusted with relation to the arms 25 of the two-armed levers 24, 25, so that the action is adjustable. The ends of the arms 25 of the two-armed levers 24, 25 are only then in the path of the adjusting screws 49 when the levers with the combs *c* and *d* are in their foremost position. Since in the drawing this is only true of one of the combs, only that comb which is in the foremost position will rise.

The foremost thread released by the move-

ment of the combs *c*, *d* in the lease in the manner to be described is within the range of the pressure and suction air currents in the mouth 50, 51 on the swinging arm 52 which is swingable about a bolt 53 secured to the side wall 3 of the frame and pressed by means of a spring 54 in the axial direction against the controlling casing 55. The sliding surfaces of the hub of the swinging arm 52 and of the control casing are ground together. In the control casing emerges the pressure piping 56 and the suction piping 57 which are connected to the pressure and suction pipe of an air pump or fan. In that wall of the control casing 55 facing the swinging arm 52 there are situated the mouths 56¹, 57¹ of the pressure and suction air piping and the adjacent side of the hub possesses corresponding openings which 20 form the mouth of suction and pressure pipings which pass through the hub of the swinging arm and the arm itself as far as the mouth. The pressure air piping 58 is led to the hook-shaped ends 50¹, 51¹ of the jaws 50, 51 and correspondingly branched (Figs. 4-7). The mouths of the pressure piping are situated on the inner sides 50'', 51'' of the hook ends of the mouth 50, 51 and are directed toward the throat in which are 30 situated the mouths 59', 59'' of the suction air piping 59. The mouth 50, 51 is divided cross-wise and between its parts there can enter a gripper hook 60 which can grasp, hold fast and guide to the feeding device the thread which is blown into the throat of the mouth 50, 51 by the current of compressed air flowing from the nozzles 50'', 51'', and simultaneously sucked by the suction nozzles 59', 59'' into the throat, after the swinging arm 52 is swung from its working position (Fig. 5) into that position (Fig. 6) in which it lies outside the path of the released thread, so that this latter can pass beneath said swinging arm. The mouth 50, 51 on the 40 swinging arm 52 and the gripper 60 work in the center of the lease. In the working position of the mouth 50, 51, the pressure and suction piping mouths of the control casing coincide with those of the swinging arm 52 (Fig. 5), while with the mouth swung out of the working position (Fig. 6), the openings no longer coincide, so that unnecessary waste of air is avoided. The swinging arm 52 is actuated against the action of a spring 55 61 by means of a cam 62 on the driving shaft 22. This shaft is surrounded by the forked end of a connecting rod 63 on which is rotatably mounted a roller 64 bearing against the periphery of the cam 62 and which connecting rod engages with a short arm 65 on the hub of the swinging arm 52. On the second arm 66 on the hub of the swinging arm is secured one end of a tension spring 61 whose other end is hooked to a pin 67 on 60 the wall 3 of the frame.

From the shaft 22 the gripper 60 also receives its movement. The hook of this gripper is provided, for example with two prongs, so that the separated thread which is held by the mouth 50, 51 of the swinging arm 52 is engaged by the fork of the hook. The bar of the gripper 60 is a two-armed lever 71, 72 whose pivot 73 is situated upon the longer downwardly directed arm of a bell-crank lever 74, 75 which is swingably arranged upon a shaft 76 mounted in the side walls 2, 3 and whose arm 75 is under the influence of a tension spring 77 which at one end engages with the arm 75 and at the other end is secured to the frame wall. On 80 the arm 74 of the bell-crank lever 74, 75 there engages a connecting rod 78 whose forked end engages with the shaft 22 and which carries a roller 79 which bears against a cam 80 on the shaft 22. This cam acts 85 against the spring 77 which presses the roller 79 against the cam. The arm 72 of the bar of the gripper hook 60 carries at the end a lateral pivot 68 which is guided by a guide consisting of a fixed 90 guide-block 69 and a resilient movable guide tongue 70 and pressed by means of a spring 81 on to the guiding surfaces, which said spring engages at one end with the arm 74 of the bell-crank lever 74, 75 and at the 95 other end with the arm 72 of the gripper bar. The above mentioned guide imparts to the gripper hook an upward and downward oscillation on its to and fro movement along the lease rods caused by the cam 80. The 100 gripper carries the thread engaged by same to an endless stepwise movable gripper chain 82 which runs over fixed chain rollers 83, 84, on pivots 85, 86 on the side wall 2 of the frame, and which chain is further 105 guided by fixed guide rails 87, 88 and 89, behind the chain roller 83 in such a manner that a part of the chain runs parallel with the lease rails and then somewhat suddenly 110 upward toward the chain roller 84. The individual members of the gripper chain 82 possess outwardly directed fingers 90 which engage and carry along the thread guided to and deposited before same by the gripper hook 60. Consequently, as shown 115 in Figs. 2 and 16-18, there are always at least four threads at the same time in readiness to be manipulated. The gripper chain is given a stepwise movement and executes a forward step when the shaft 22 makes one revolution. For this purpose there is rigidly connected with the chain wheel 84 a ratchet wheel 91 in which engages a pawl 92 on a lever 93 which likewise swings about the pivot 86 and is connected by means of a connecting rod 94 with the arms 95 of a V-shaped lever 95, 96 which is secured to a 120 rocking shaft 97 mounted in the frame walls 2, 3. On the arm 96 of the lever 95, 96 there engages the rod 98 of an eccentric 99 mount. 125 130

ed on the shaft 22. The joint balls 100, 101 of the connecting rod 94 and of the eccentric rod 98 are arranged adjustably in radial direction in adjusting slots 102, 103 of the arms 95, 96 for the purpose of regulating the stroke. The ratchet wheel 91 is thus turned one tooth on each rotation of the driving shaft 22. On each ratchet movement, the gripper chain 82 moves one complete step forward, so that by the next finger 90 the released thread is grasped and taken along. From the ratchet gear 91, 92 there is also driven the shaft 21. On each rotation of the ratchet wheel 91 for one tooth, the shaft 21 is rotated for half a revolution corresponding to the rotation of the eccentric 19, 20 about 180°. For this purpose a gear wheel 104 is secured to the ratchet wheel 91, said gear wheel engaging in a similar wheel 105 on the shaft 21. The separated threads are manipulated while being held together by the fingers 90 of the gripper chain 82. The completed threads are engaged by a gripper hook 106 and led farther, said hook being situated on the arm 107 of a two-armed lever 107, 108. The pivot 109 of the latter is arranged on the arm 110 of a two-armed lever 110, 111 which swings about a fixed pivot 112 and which is connected by means of a connecting rod 113 with a lever arm 114 on the shaft 97. The connecting pivot 115 is adjustable in an adjusting slot 116 of the arm 114 in order to regulate the stroke. The end of the arm 108 of the lever 107, 108 is provided with a lateral pin 117 which is controlled by means of a guide consisting of a fixed guide block 118 and a movable guide tongue 119. The pivot 120 of the guide tongue 119 passes through a projection 21 of the wall 2 and carries on the other side a lever arm 121. On this latter there engages a spring 122 which tends to force the tongue 119 against the block 118. The lever arm 121 is further connected by means of connecting rod 123 with the shorter arm 124 of a bell crank lever 124, 125 which swings about a fixed pivot 126 and whose longer arm 125 ends in a hook 127. This latter serves for temporarily holding the finished manipulated threads. The eccentric 99 imparts to the gripper hook 106 its to and fro movement in which, by means of the guides 118, 119, said hook executes an upward and downward swinging motion. If the guide tongue, on the through-passage of the lateral pin 117 during the return movement of the gripper hook 106, is forced away from the guide block 118, then the holding hook 127 is given an upward movement, whereby it from time to time releases the threads held fast by same and then immediately, after the gripper hook 106 has fed the next thread, returns into its position of rest. During the period in which the hook 127 releases the threads

they are held together with the new threads by the gripper hook 106.

In order to push back the remaining lease threads into the correct position after the separation of a thread, so that when working quickly the chain is prevented from grasping the remaining threads, a thrust-lever 128 is provided which forms the longer arm of a two-armed lever 128, 129. This latter is rotatable upon a pivot 130 secured to the casing wall. On the arm 129 there engages a tension spring 131 which at the other end is hooked to a pin 132 on the frame wall 3. On the arm 129 there is further jointed a connecting rod 133 whose other forked end surrounds the shaft 21 and lies with a roller 134 against a double cam 135 on the shaft 21. The thrust lever 128 thus receives on each rotation of the shaft 21 a working movement.

The method of working of the device is as follows:—In the initial position (Figs. 3 and 9) the combs *c* and *d*, on account of the pawls 34 which hold said combs in the initial middle position during the reverse being released by contacting with the stops 38, are brought into the lower position in which their shorter prongs engage with the appertaining lease threads *a* or *b*, so that they engage with a large number of the foremost threads. In Fig. 9, *a*¹ is the foremost thread in the lease. As this thread is to be first separated, there is imparted to the comb *c* a forward movement along the lease bars. This is effected by the eccentric 19 on the shaft 21. The comb *d* simultaneously returns into the initial position and in the lower position into which it arrives it engages with the lease threads *b* and holds same fast. The threads now assume the position shown in Fig. 10. The thread *a*¹ now lies quite apart from the remaining threads, the threads *a*² and *a*³ being held back in the middle of the lease by the threads *b*¹ and *b*² crossing same, and the thread *a*¹ forms the base of a triangle whose opposite sides are formed by the threads *a*², *a*³ and *b*¹, *b*². At this moment the mouth 50, 51 of the swinging arm 52 comes over the separated thread *a*¹ which is now held in the throat of the mouth by the air currents, so that the gripper 60 comes over, descends and grasps said thread *a*¹. The mouth 50, 51 (Fig. 11) now swings back and the gripper 60 guides the separated thread *a*¹ to the gripper chain 82 whose fingers 90 engage the thread on the following forward movement of the gripper chain. The foremost of the threads carried by the fingers of the gripper chain 82 and which is now ready to be manipulated is grasped during the last mentioned operation by the gripper hook 106 which brings the thread in the described manner behind the holding hook 127. When the mouth 50, 51 has grasped the 130

separated thread a^1 , the latter can be released by the comb c . For this purpose the latter is raised by the arm 40 in its foremost position into its highest position in the 5 manner described (shown dotted in Fig. 3). The threads a^2 , a^3 now spring back under their own tension and the thrust lever 128 insures the complete closing up of the threads a^2 , a^3 and b^1 , b^2 . The arm 40 then 10 returns into its position of rest. The comb c is released and, in consequence of the action of the spring 27 sinks into its middle position in which, by means of the notch 37 of the pawl 34 it is held during the return 15 movement which it executes on the next movement of the ratchet gear 91, 92, while simultaneously the comb d is moved forward. In the middle position, the forward longer prong c^1 of the comb c strikes against 20 the previously brought forward threads a^2 , a^3 when the comb c arrives in its initial position in which it again engages with the threads a when passing from the middle position (dotted in Fig. 12) into the lower 25 position (full lines in Fig. 12), then holding fast said threads a . The comb d moved forward in the lower position has taken with it the threads b^1 , b^2 , b^3 and results in the position of the threads shown in Fig. 13, in 30 which the now foremost thread b^1 is separated from the remaining threads in the same manner as previously occurred with the thread a^1 . The comb d now receives from the appertaining arm 40 in its foremost 35 position, its upward movement into the highest position, whereby all threads are released after the mouth 50, 51 has taken up the separated thread b^1 which is now 40 grasped by the gripper 60. The threads b^2 , b^3 swing back under their own tension and are pushed back by the thrust lever 128 to the remaining lease. The comb d is then again released during its downward movement by the spring 27 and arrives on 45 the nose 37 of the appertaining pawl 34, so that it is now situated in the middle position. The combs c and d now again change their positions by means of the eccentrics 20, 21 in consequence of the further movement 50 of the ratchet gear 91, 92 to the extent of one tooth. The comb d returns into the middle position (Fig. 14) and, having arrived in the initial position and returning into its lower position by the release of the 55 pawl 34, engages and holds fast the remaining threads b , while the comb c carries the thread a^2 forward with the following threads. The thread b^1 has in the meantime been transferred to the gripper chain 60 82 by the gripper 60 and the gripper hook 106 has brought a completed thread behind the holding hook 127. The operation is repeated continually in the manner above described.

65 It is clear that the change in position of

the combs c and d need not necessarily take place simultaneously, as illustrated. The one comb may remain in the initial position until the other has returned into its initial position. This has been assumed in 70 Figs. 9-15 in order to be able to better illustrate the different positions of the threads. It is further clear that the holding back of the threads lying dissimilarly to the thread to be separated, and the drawing forward of 75 the threads lying similarly to the thread to be separated cannot only be effected above one of the lease rods, but also below, or above and below. The illustrated device works in the same manner below the warp as 80 above the warp and can therefore be arranged below the warp instead of above as shown in the drawings.

Having now described my invention what I claim as new and desire to secure by Letters Patent is:-

1. In a machine for separating the foremost thread in the lease of textile warps, the combination, of means for seizing and holding the thread adapted to reciprocate 90 vertically and horizontally along the lease rods, means whereby said first named means engage, in their initial position and during their forward movement, with the corresponding threads in such a manner that 95 one of said first named means holds back the threads held thereby, while the other of said first named means carries forward the foremost of its threads, a gripping device, and a conveying device, substantially as 100 hereinbefore described and for the purpose specified.

2. In a machine for separating the foremost thread in the lease of textile warps, the combination of combs adapted to reciprocate 105 vertically, and horizontally along the lease rods, means whereby said combs engage, in their initial position and during their forward movement, with the corresponding threads in such a manner that the one comb 110 holds back the threads held thereby, while the other comb carries forward the foremost of its threads, the foremost prong of each of said combs being longer than the remaining combs, means whereby said 115 combs are moved only to such an extent upward or downward during the return movement into the initial position, that the foremost prong engages with the threads which have sprung back under their own tension, 120 a gripping device and a conveying device, substantially as described and for the purpose specified.

3. In a machine for separating the foremost thread in the lease of textile warps, 125 the combination of combs adapted to reciprocate vertically, and horizontally along the lease rods, means whereby said combs engage, in their initial position and during their forward movement, with the corre-

- sponding threads in such a manner that the one comb holds back the threads held thereby, while the other comb carries forward the foremost of its threads, the foremost 5 prong of each of said combs being longer than the remaining combs, means whereby said combs are moved only to such an extent upward or downward during the return movement into the initial position, that the 10 foremost prong engages with the threads which have sprung back under their own tension, a gripping device and a conveying device, means for resiliently forcing said combs into engaging position, means for 15 raising or lowering said combs in their front end position, means for arresting said combs in a middle position, and means for releasing said arresting means, substantially as described and for the purpose specified.
- 20 4. In a machine for separating the foremost thread in the lease of textile warps, the combination of combs adapted to reciprocate vertically, and horizontally along the lease rods, means whereby said combs engage, in their initial position and during their forward movement, with the corresponding threads in such a manner that the one comb holds back the threads held thereby, while the other comb carries forward the 25 foremost of its threads, the foremost prong of each of said combs being longer than the remaining combs, means whereby said combs are moved only to such an extent upward or downward during the return movement 30 into the initial position, that the foremost prong engages with the threads which have sprung back under their own tension, means for resiliently forcing said combs into engaging position, means for raising or lowering said combs in their front end position, means for arresting said combs in a middle position, and means for releasing said arresting means, air suction nozzles, air pressure nozzles, means whereby the foremost comb 35 brings the separated thread into the range of the air currents of said nozzles, a gripping device for engaging said thread, and a conveying device, substantially as described and for the purpose specified.
- 40 5. In a machine for separating the foremost thread in the lease of textile warps, the combination of combs adapted to reciprocate vertically, and horizontally along the lease rods, means whereby said combs engage, in their initial position and during their forward movement, with the corresponding threads in such a manner that the one comb holds back the threads held thereby, while the other comb carries forward the 45 foremost of its threads, the foremost prong of each of said combs being longer than the remaining combs, means whereby said combs are moved only to such an extent upward or downward, during the return movement 50 into the initial position, that the foremost

prong engages with the threads which have sprung back under their own tension, means for resiliently forcing said combs into engaging position, means for raising or lowering said combs in their front end position, 70 means for arresting said combs in a middle position, and means for releasing said arresting means, a swinging arm, a mouth therein, air suction nozzles mounted in the throat thereof, air pressure nozzles mounted at the ends of the jaws of said mouth and directed toward said suction nozzles, a gripping device for engaging said thread, and a conveying device, substantially as herein described and for the purpose specified.

6. In a machine for separating the foremost thread in the lease of textile warps, the combination of combs adapted to reciprocate vertically, and horizontally along the lease rods, means whereby said combs engage, in their initial position and during their forward movement, with the corresponding threads in such a manner that the one comb holds back the threads held thereby, while the other comb carries forward the 80 foremost of its threads, the foremost prong of each of said combs being longer than the remaining combs, means whereby said combs are moved only to such an extent upward or downward during the return movement into the initial position, that the foremost prong engages with the threads which have sprung back under their own tension, means for resiliently forcing said combs into engaging position, means for 85 raising or lowering said combs in their front end position, means for arresting said combs in a middle position, and means for releasing said arresting means, a swinging arm, a mouth therein, air suction nozzles mounted in the throat thereof, air pressure nozzles, mounted at the ends of the jaws of said mouth and directed toward said suction nozzles, a gripping device for engaging said thread, a conveying device, means whereby said swinging arm is moved into the initial position on the feeding of the thread by the comb, and means whereby said arm is swung out of the path of the separated thread after the latter has been grasped by the gripping device, substantially as described and for the purpose specified.

7. In a machine for separating the foremost thread in the lease of textile warps, the combination of combs adapted to reciprocate vertically, and horizontally along the lease rods, means whereby said combs engage, in their initial position and during their forward movement, with the corresponding threads in such a manner that the one comb holds back the threads held thereby, while the other comb carries forward the foremost of its threads, the foremost prong of each of said combs being longer than the remaining combs, means whereby 125

5 said combs are moved only to such an extent upward or downward during the return movement into the initial position, that the foremost prong engages with the
 10 threads which have sprung back under their own tension, means for resiliently forcing said combs into engaging position, means for raising or lowering said combs in their front end position, means for arresting said combs in a middle position, means for releasing said arresting means, a swinging arm, a mouth therein, air suction nozzles mounted in the throat thereof, air pressure nozzles mounted at the ends of the jaws of
 15 said mouth and directed toward said suction nozzles, a gripping device for engaging said thread, a conveying device, means whereby said swinging arm is moved into the initial position on the feeding of the
 20 thread by the combs, and means whereby said arm is swung out of the path of the separated thread after the latter has been grasped by the gripping device, and means whereby the air pressure and suction currents are controlled by the oscillations of
 25 said swinging arm, substantially as described and for the purpose specified.

8. In a machine for separating the foremost thread in the lease of textile warps, 30 the combination of combs adapted to reciprocate vertically, and horizontally along the lease rods, means whereby said combs engage, in their initial position and during their forward movement with the corresponding threads in such a manner that the
 35 one comb holds back the threads held thereby, while the other comb carries forward the foremost of its threads, the foremost prong of each of said combs being longer than the remaining combs, means whereby
 40 said combs are moved only to such an extent upward or downward during the re-

turn movement into the initial position, that the foremost prong engages with the 45 threads which have sprung back under their own tension, means for resiliently forcing said combs into engaging position, means for raising or lowering said combs in their front end position, means for arresting said 50 combs in a middle position, and means for releasing said arresting means, a swinging arm, a mouth therein, air suction nozzles mounted in the throat thereof, air pressure nozzles mounted at the ends of the jaws of 55 said mouth and directed toward said suction nozzles, a gripping device for engaging said thread, means whereby said swinging arm is moved into the initial position on the feeding of the thread by the combs, 60 and means whereby said arm is swung out of the path of the separated thread after the latter has been grasped by the gripping device, and means whereby the air pressure and suction currents are controlled by the 65 oscillations of said swinging arm, a conveying member, fingers thereon, means whereby said gripping device feeds the separated thread to said conveying member, means whereby said chain is guided parallel 70 to the lease rods at the place where the threads are manipulated, and means whereby the thread, at the end of the parallel path is fed to a second gripper, a holding hook for the completed threads, and means 75 whereby said second gripper conveys the thread to said holding hook, substantially as described and for the purpose specified.

In testimony whereof I have signed my name to this specification in the presence 80 of two subscribing witnesses.

MAX WENZEL.

Witnesses:

WOLDEMAR HAUPT,
HENRY HASPER.
